UNITED STATES PATENT OFFICE.

JAMES H. C. BOIG, OF LIVERPOOL, ENGLAND.

DESIGN FOR A PUZZLE-CARD.

SPECIFICATION forming part of Design No. 27,127, dated June 1, 1897.

Application filed December 21, 1896. Serial No. 616,547. Term of patent 3½ years.

To all whom it may concern:

Be it known that I, JAMES HENRY COGH-
LAN BOIG, master mariner, a subject of the
Queen of Great Britain and Ireland, residing
5 at 10 Rossett Avenue, Liverpool, England,
have invented a new and original Design for
a Puzzle-Card, of which the following is a
specification.

In the drawings, Figure 1 is a plan, and
10 Fig. 2 is a sectional view, of the design.

The design consists in a disk or plate *a*,
having a series of perforations *b* therein in
the form of a St. George's cross, the perfora-
tions being connected by lines clearly defin-

ing this form of cross. A series of peripheral 15
perforations *c* extend about the cross form,
and lines connect these with each other and
with the other perforations.

I claim—

The design for a puzzle-card substantially 20
as herein shown and described.

In witness whereof I have hereunto set my
hand in presence of two witnesses.

J. H. C. BOIG.
